UNITED STATES PATENT OFFICE.

ERROL M. MOLLETT, OF SACRAMENTO, CALIFORNIA.

ROTARY ELECTRIC ENGINE.

Application filed December 22, 1927. Serial No. 241,840.

This invention relates to a rotary electric engine adapted for a variety of uses, such as running dynamos, fan blowers and other machinery, or propelling boats and the like.

5 The primary object of the present invention is to provide an improved form of rotary electric engine having maximum power and embodying a plurality of electric motors arranged to direct the drive and 10 revolve with a rotary shaft.

A more specific object is to provide an engine of the above kind in which the momentum of the revolving motor is utilized to advantage for power purposes, and in 15 which the load of friction is minimized by doing away with counter-shaft pulleys, gear trains, belts and belt tighteners.

A still further object is to provide a rotary electric engine of the above kind which 20 is extremely simple and durable in construction, which may be readily assembled or taken apart for repair, and which is thoroughly reliable in operation.

Still another object is to provide, in an 25 engine of the above kind, simple and efficient means for reversing the direction of rotation of the motors and shafts driven thereby.

The invention consists in the novel form, 30 combination and arrangement of parts hereinafter more fully described, shown in the accompanying drawings and claimed.

In the drawings, wherein like reference 35 characters indicate corresponding parts throughout the several views,

Figure 1 is a view partly in central longitudinal section, partly in side elevation, and partly broken away, of a non-reversible rotary electric engine constructed in accordance with the present invention;

Figure 2 is an enlarged fragmentary section taken upon line 2—2 of Figure 1;

Figure 3 is a view similar to Figure 1 of a modified form of engine in which means is provided for reversing the direction of rotation of the motors and driven shaft;

Figure 4 is a section on line 4—4 of Figure 3;

Figure 5 is a vertical transverse section taken on line 5—5 of Figure 3;

Figure 6 is an enlarged fragmentary section taken on line 6—6 of Figure 3; and

Figure 7 is an enlarged fragmentary plan view showing the means for effecting and maintaining the desired direction of drive for the shaft of the motor shown in Figure 3.

Referring more in detail to the drawings, each form of the invention includes a pair of spaced stationary supports 5 and 6 in which is journaled a rotary drive shaft 7 having an enlargement 8 at a point between the uprights 5 and 6 and preferably composed of a pair of sections rigidly bolted together as at 9 in coaxial relation, the adjacent ends of the shaft sections being axially recessed to provide the enlargement 8 with a chamber 10, and the end of one shaft section fitting within the end of the other shaft section as shown clearly in Figures 1 and 3. The chambered enlarged portion 8 of one of the shaft sections is provided with radial openings 10, and rigidly and detachably bolted as at 11 to the periphery of the enlargement 8 are suitable castings or posts 12 having radially extending bores registered with the openings 10. The casing or frame of a rotary-armature electric motor 13 is rigidly and detachably bolted as at 14 to the outer end of each casting or post 12 so that the armature shaft of the electric motor is disposed radially to the shaft 7 and projects inwardly through and is journaled in the adjacent post or casting 12 as shown. The inner end of each armature shaft projects inwardly through the adjacent opening 10a in the chamber 10 of the enlargement 8 of shaft 7, where it is provided with a pinion 15. The inner end portion of shaft 7 is provided with an axial passage or bore 16 into which projects a supporting rod 17 that is suitably restrained against rotation and projects into the chamber 10 of the shaft enlargement 8 where it supports a gear track or wheel 18 adapted to be suitably held against rotation or stationary and with which the pinions 15 that are fixed on the armature shafts of the motor 13 are meshed. The motors 13 are of any well known or conventional construction except that suitable packing means is provided for retaining the oil in the armature shaft bearings.

A suitable support 19 is mounted in a stationary position at one side of the enlargement 8 and carries suitable brushes 20 and 21 respectively adapted to continuously engage annular collector rings or wheels 22 and 23 secured upon the shaft 7. The respective feed and return wires 24 and 25 are connected to the brushes 20 and 21, and the respective wires of the motors are similarly connected to the respective collector

wheels or rings 22 and 23, as clearly shown. In this way, the current collected from the brushes by the collector rings 22 and 23 is carried to the motors.

5 In the form of the invention shown in Figures 1 and 2, the track gear 18 is fixed upon the inner end of the supporting rod 17, and the latter has its outer end slidably keyed as at 26 in a post 27 supported by a 10 bracket 28 carried by the adjacent support 5. In this way, the rod 17 may be longitudinally adjusted to effect the proper meshing of the gear 18 with the pinions 15 even after wear takes place, the adjustment 15 of the rod 17 being suitably maintained such as by means of a set screw 29 carried by the post 27 and adapted to impinge the rod 17.

In the construction shown in Figures 3 to 8 inclusive, the track gear 18 is revolvably mounted on the supporting rod 17 at 20 one side of the radial plane intersecting the armature shafts of the electric motors 13, and a further track gear 30 is similarly mounted on the rod 17 at the opposite side 25 of said plane so as to mesh with the pinion 15 at the opposite side of the latter from that at which the track gear 18 meshes therewith. In this form of the invention, the hubs of the track gears 18 and 30 are provided at their outer ends with female clutch elements 31 and 32, while male clutch elements 33 and 34 are fixed upon the supporting rod 17 so that by sliding the latter longitudinally either of the clutch elements 33 or 34 may be engaged with its respective 30 cooperating clutch element 31 or 32. The arrangement is also such that both of the clutch elements 33 and 34 may be simultaneously disengaged from the cooperating 35 clutch elements 31 and 32 for allowing both of the track gears 18 and 30 to idle freely on the rod 17. Naturally, when clutch element 33 is engaged with clutch element 31, the track gear 18 will be held stationary 40 while the track gear 30 will be permitted to freely revolve on the rod 17, and when clutch element 34 is engaged with clutch element 32, the track gear 30 will be held stationary with rod 17, while the track gear 18 is allowed to freely rotate on said rod 45 17. In this form of the invention, the set screw 29 is dispensed with and the adjacent projecting end of rod 17 has a lateral lever 35 fixed thereto as shown in Figure 7, 50 said lever having a suitable catch 36 arranged to engage selectively in the notches 37 of a rack bar 38 fastened to the lateral projection 39 of post 27 and extending parallel with the rod 17. It will thus be seen 55 that by releasing the catch 36, the lever 35 may be utilized to slide the supporting rod 17 and effect the desired clutch operation, the catch 36 being allowed to engage in a notch 37 to hold the rod 17 adjusted in any 60 of the three positions referred to above, 65

namely, where clutch element 33 is engaged with clutch element 31, where clutch element 34 is engaged with clutch element 32, and where both clutch elements 33 and 34 are disengaged from clutch elements 31 and 32. 70 As this form of the invention provides for reverse drive of the shaft 7, it is desirable to have a means for retarding the rotation of shaft 7 and bringing the engine to a standstill when the motors have been 75 thrown out of operation so that the desired change of gear may be readily effected without undue delay. For this purpose a brake wheel 39 is fixed upon the shaft 7 and an arcuate brake shoe 40 is adapted to be manually pressed into engagement with the periphery of this brake wheel. The brake shoe 40 is preferably carried by a vertically 80 slidable plunger rod 41 mounted in a hollow post 42 carried by the engine foundation 43 upon which the posts or supports 5, 6 and 19 are mounted. The rod 41 is spring 85 pressed as at 44 to normally release the brake shoe, and the lower end of said rod 40 is engaged by one end of a pivoted lever 45 mounted in a recess 46 of the foundation 43 so that when the other end of the lever is depressed, the brake shoe will be elevated and engaged with the brake wheel. The said other end of lever 45 projects upwardly through the foundation 43 where it is provided with a suitable operating pedal 47. 90

In the preferred construction, the collector wheels 22 and 23 are preferably provided with resilient longitudinally split hubs which are engaged by threaded cone nuts or rings 48 so as to clamp the collector wheels firmly on the shaft 7 to rotate with the latter. 100

From the foregoing description it will be seen that when the current is supplied through wires 24 and 25 it will pass through brushes 20 and 21 and collector rings 22 and 23 to the motors 13. The armature shaft of the motor will thereupon revolve and the pinions carried thereby will be rotated and caused to travel around the track gear which is held stationary, said track gear being the single track gear of Figure 1 or 110 either desired one of the track gears 18 and 30 of Figure 3. As the armature shafts revolve and the pinions 15 travel around the stationary track gear, the motors 13 and the shaft 7 are caused to revolve 115 about the axis of the shaft 7. In either form of the invention, the power of the invention may be transmitted directly from the shaft 7 by any suitable means. 120

In the form of the invention shown in 125 Figure 3, the motors 13 will be caused to bodily revolve with the shaft 7 in one direction when the clutch element 33 is engaged with clutch element 31 to hold the track gear 18 stationary, and a reversed ro- 130

tation of the motors and shaft 7 will be effected upon allowing the track gear 18 to run idle on the supporting rod 17 and clutching the track gear 30 to said rod 17 by engagement of clutch element 34 with clutch element 32. While the form of the invention shown in Figure 1 is particularly serviceable for use in running dynamos, fan blowers and the like where reverse drive is not essential, the form of the invention shown in Figure 3 may be utilized to advantage where reverse drivers are desired such as in the propulsion of boats and the like.

Obviously, various changes may be made in the construction of the engine without departing from the spirit and scope of the invention as claimed. For example, while the engines illustrated herein involve only two electric motors mounted in opposed relation, it is apparent that the number of motors used may be readily increased to three or more by arranging the motors in equally spaced relation about the shaft 7 and providing each of them with armature 25 pinions meshing with the track gear or gears.

What I claim as new is:—

1. The combination with a chambered rotary drive shaft, of a stationary track gear in the chamber of said shaft, an electric motor fixed on said shaft with its armature shaft arranged radially to said drive shaft and projecting into the chamber of the latter, a pinion carried by the armature shaft of said motor and engaged with said stationary track gear, and electric connections to said motor.

2. The combination with a chambered rotary drive shaft, of a stationary track gear in the chamber of said shaft, an electric motor fixed on said shaft with its armature shaft arranged radially to said drive shaft and projecting into the chamber of the latter, a pinion carried by the armature shaft of said motor and engaged with said stationary track gear, electric connections to said motor, said drive shaft having an axial

bore, and a stationary supporting rod extending through said bore into said chamber and having the track gear mounted thereon.

3. The combination with a chambered rotary drive shaft, of a stationary track gear in the chamber of said shaft, an electric motor fixed on said shaft with its armature shaft arranged radially to said drive shaft and projecting into the chamber of the latter, a pinion carried by the armature shaft of said motor and engaged with said stationary track gear, electric connections to said motor, said drive shaft having an axial bore, and a stationary supporting rod extending through said bore into said chamber and having the track gear mounted thereon, said drive shaft embodying interfitting coaxial sections having enlarged and recessed connected ends.

4. The combination with a rotary drive shaft, of a pair of spaced circular tracks, electric motors fixed on said drive shaft with their armature shafts radial to the latter, wheels on said armature shafts engaged with said tracks, means to selectively hold either desired track stationary, and electric connections to said motors.

5. The combination with a rotary drive shaft, of a pair of spaced circular tracks, electric motors fixed on said drive shaft with their armature shafts radial to the latter, wheels on said armature shafts engaged with said tracks, means to selectively hold either desired track stationary, electric connections to said motors, said drive shaft having an axial bore, a non-rotatable supporting rod slidably extending through said bore and on which said tracks are loosely mounted, and cooperating clutch elements carried by the tracks and supporting rod, whereby the latter may be slid to selectively clutch either desired track thereto and thereby hold said track stationary.

In testimony whereof I affix my signature.

ERROL M. MOLLETT.
